UNITED STATES PATENT OFFICE.

ROBERT L. McELROY, OF NEW YORK, N. Y.

WRENCH.

1,222,780.

Specification of Letters Patent. Patented Apr. 17, 1917.

Application filed December 23, 1915. Serial No. 68,329.

To all whom it may concern:

Be it known that I, ROBERT L. McELROY, a citizen of the United States, residing in New York, in the county of New York and 5 State of New York, have invented certain new and useful Improvements in Wrenches, of which the following is a specification.

This invention relates to the general class of tools, and more particularly to a wrench 10 for use with automobile curtains.

The main object of the present invention is to provide a tool adapted for use with an automobile curtain of the type having gromets coöperating with buttons secured to 15 an automobile body to attach such automobile curtain to such automobile body, by means of which tool, the curtain is, when necessary, quickly stretched into place so that the buttons can readily pass through 20 the gromets and be turned to properly attach the curtain.

A particular feature of the present invention is a tool which can be readily manipulated both to function as a lever, similar to 25 a button shoe-hook, so as to position a gromet of a curtain over a button of an automobile body and thereupon to be manipulated to draw the curtain down so that the gromet can, with facility, be passed over the 30 button and the button thereupon turned to attach the thereto connected portion of the curtain in place.

Still another feature of the invention is 35 the provision of a cam which will afford a fulcrum perch to permit one side of the tool to be swung away from the curtain being attached in one step of the operation and thereupon permit the other side of the tool to be swung away from the curtain in a 40 succeeding step of the operation.

These and other features, capabilities and advantages of the present improvement will 45 more fully appear from the subjoined detail description of one specific embodiment thereof, in which—

Figure 1 is an edge view of my improved combination tool.

Fig. 2 is a side or face view thereof.

Fig. 3 is an enlarged fragmental side view 50 of the wrench portion thereof.

Figs. 4, 5 and 6 are fragmental views illustrating diagrammatically a button of an automobile body, a part of the curtain to be attached, and the wrench in successive positions in the operation of such wrench.

In the embodiment shown, a shank S is

provided having at one end a wrench W and at the other end an enlargement E which may serve as the handle when using the wrench W, and which is furthermore formed into a 60 combination tool having a conformation 11 for use as a bottle opener, conformations 12, 13 and 14 corresponding to various size end wrenches to serve as such, a conformation 15 for use as a scraper, and a conformation 16 65 for use as an alligator wrench. Obviously, when any of the conformations 11 to 16 are used, the end W of the shank S would be used as the handle.

The part of the shank S approaching the 70 wrench W is provided with a curved portion 17 comparatively slender to form a fulcrum zone hereinafter to be described. The convex surface 18 of the curved portion 17 terminates in a comparatively sharp turn forming the outwardly extending face 19, while the concave surface 20 terminates in a comparatively gradually curved convex face 21, (see Figs. 2 and 3). The side portions of the shank S at the end W terminate in jaws 80 23 suitably spaced from one another and extending beyond a cam surface substantially concave in contour and comprising essentially an outer side face 25, usually slightly curved, as shown, at a right angle to the face 85 26 of the jaws 23, which are adjacent to the face 19, and an opposing side 27 of substantially the curved contour shown, which forms the inner side of the lip 28 of which the face 19 forms the outer side. The edges 90 26 are comparatively straight as compared to the other two edges 29 of the jaws 23 which are continuations of the gradually curving face 21 of the shank S.

The wrench W just described is intended 95 especially for use with the buttons of automobile bodies which coöperate with gromets of an automobile curtain to attach an automobile curtain to an automobile body.

In Figs. 4, 5 and 6, successive positions 100 of the wrench W in the course of its operation are diagrammatically shown, together with an automobile body and curtain being attached thereto. To the body 30 of the automobile, a bearing 31 is suitably secured 105 to which is pivotally connected the button 32 which is rather narrow in thickness, as shown in Fig. 6, as compared to its width, as shown in Figs. 4 and 5.

The gromet 33 of the automobile curtain 110 34 is of the usual construction, somewhat narrower in width than the width of the

button 32 so that when the button 32 is turned into the position shown in Fig. 6, the curtain 34 will be securely attached in place.

- 5 The operation of the wrench W is as follows: The wrench W is passed through the gromet 33 of the curtain 34 so that the gromet is disposed on the curved portion 17 of the shank S, as shown in Fig. 4, there-
10 upon the jaws 23 of the wrench W are moved into engagement with the button 32 so that the faces 25 and 27 of the cam of such wrench will come into contact with the buttons; then the wrench W is moved in
15 the direction of the arrow 35 (Fig. 4) until the wrench W occupies the position indicated by the dotted lines 36; thereupon the wrench W and the therewith engaged button are rotated a full 180 degrees, the curved
20 portion 17 of the shank S turning around in the gromet 33; thereupon the wrench W is depressed to the position shown in Fig. 5, in which position the curtain 34 may readily be pressed down over the bearing 31;
25 and thereupon the button 32 turned 90 degrees to the position shown in Fig. 6 where it securely locks the curtain 34 to the body
30. As shown in Fig. 5, when the wrench has been turned to the position shown in
30 such figure, by the pressure of the oper-

ator's fingers at the point 37, the curtain 34 may, with facility, be pressed over the bearing 31. When the curtain has been pressed onto the bearing 31, the button 32 may be turned either by the operator's fingers or by
35 the turning of the wrench W.

It will, of course, be understood that various changes and modifications may be made to the details of construction without departing from the general spirit or scope of 40 the invention.

I claim:

An implement for drawing a gromet over a rotatable button and for thereafter rotating the button comprising a shank, a head 45 adapted to pass through the gromet secured to one end of said shank and extending beyond one side thereof, the head and shank being so shaped that their outer surfaces merge to form an unbroken curved surface, 50 said head being recessed in the plane of the shank to form spaced walls for engaging the parallel sides of said button, and a third wall forming a lip which extends from and merges into the side of said shank.

ROBERT L. McELROY.
